VENTILATOR SYSTEM FOR WATER CLOSETS

Harold Mitton, Drummond, Mont.

Application July 14, 1947, Serial No. 760,855

4 Claims. (Cl. 4—216)

1

The present invention refers to water closet construction and more particularly to the ventilation thereof. The main object of my invention is to prevent odors from the closet entering the room but to lead them instead directly from the closet out into the atmosphere.

This improvement can be applied, not only to new closets, but also to closets already installed and of almost any type provided with a hinged seat and a lid.

One embodiment of my invention is illustrated in the drawing, wherein

Figure 1 is a front elevation of a water closet with both the seat and the lid in raised position;

Figure 2 is a side elevation as seen from the right side of Figure 1;

Figure 3 is a fragmentary vertical section taken on a plane along line 3—3 of Figure 1;

Figure 4 is a transverse section on a plane along line 4—4 of Figure 1 showing one manner of securing the gasket under the seat;

Figure 5 is a modification of Figure 4 showing the gasket carried in a groove under the seat;

Figure 6 is a perspective view of a flap for partly covering the vent leading into the ventilator box;

Figure 7 is a section similar to Figure 3 of a modified construction of the ventilator box.

Like numerals denote the same details in the different figures.

In the drawing numeral 10 denotes the porcelain bowl of an ordinary water closet, provided with a seat 11 open in the middle and a lid 12 as usual.

The seat 11 is hinged as at 14 on a rod 15 which is carried between two standards or hinge bolts 16 secured on top of the porcelain bowl 10. The hinge arm 14 is preferably L-shaped bent down and attached on the rear edge of the seat 11, see Fig. 3.

Another pair of hinges 17 on rod 15 placed on either side of hinges 14 are secured on the rear edge of the lid 12. The hinge rod 15 is preferably threaded in the heads 18 of the hinge bolts 16 in order to facilitate adjustment and assembling.

At 20 is shown the usual flushing tank with inlet 21 to the bowl 10 and at 22 is shown the ventilating pipe for the bowl leading out from one side of the ventilating box 23, which is shown as made of metal and set on top of the bowl 10 in Figure 3, but is shown at 23a, Figure 7, as a modification and built into the bowl 10. The ventilating box 23 has a vent opening 24 in front, which however is normally covered by an angu-

lar flap 25 provided with fingers or hooks 26 at the top for engaging under the top edge of the vent opening 24. This flap rests with its angular flange 27 on the bottom edge of the vent opening 24. It will be understood that the flap 25, the function of which is to prevent flushing water to enter the vent box 23, does not completely cover the vent opening 24, because of the triangular openings formed on each side thereof and which permits air passing thru at any time. This flap 25 can be easily removed or lifted off for repairs or for cleaning the box 23.

A cavity 30 is shown on the underside of the seat 11 at its rear end for passing odors on from the bowl 10 into the box 23 and out thru the ventilator pipe 22.

On the underside of the seat 11 and practically all around the middle opening 31 thereof is secured a gasket 32 of rubber or other flexible packing material. In Figure 4 this gasket is shown as being pressed in between the side flanges 33 of a channel 34, which is secured by screws 35 or the like.

In Figure 5 a modification is shown of carrying the gasket 32 which in that case is done by a taper sided groove 36 out into the underside of the seat 11 and surrounding the seat opening 31. The gasket 32 is squeezed into said groove 36 and held in place by the expansion of the gasket.

When the lid is closed, the gasket 32 forms an airtight closure circumscribing with the top surface of the bowl 10. Air impregnated with odors from the bowl will therefore pass out thru the cavity 30 and the side openings of the flap 25 into the ventilator box 23 and from there out into the atmosphere by means of the pipe 22. No odors will therefore escape into the room, since the gasket 32 will prevent their passage except thru the ventilator box 23, whether the construction shown in Figures 3 and 4 or in Figures 5 and 7 is used.

It is to be understood that the invention as herein disclosed may be varied from the details described and shown without departure from the spirit of the subjoined claims.

I claim:

1. A ventilator system for water closets provided with a bowl with a seat having a middle opening and a lid therefor; comprising a ventilator box with a vent in front and an outlet into the atmosphere, said box being located back of said seat at the top of said bowl, a flap over said vent having side openings forming communication between the bowl and the ventilator box,

and means for closing other outlets from said bowl.

2. A ventilator system for water closets provided with a bowl with a seat having a middle opening and a lid therefor; comprising a ventilator box with a vent in front and an outlet into the atmosphere, said box being located back of said seat at the top of said bowl, a flap over said vent having side openings forming communication between the bowl and the ventilator box, and means for closing other outlets from said bowl, said flap being hooked for easy removal in said vent.

3. A ventilator system for water closets provided with a bowl with a seat having a middle opening and a lid therefor; comprising a ventilator box positioned at the back of said seat and at the top of said bowl, said box having an outlet into the atmosphere and an inlet opening directed forwardly across the underside of the seat, the inlet opening having a bordering depending top flange, and a deflector member having connected upper and lower portions and positioned in front of the forwardly directed opening of the box, the top edge of the upper portion of said deflector

10

25

being detachably engaged behind said flange to removably maintain the deflector in position.

4. A ventilator system of the character stated in claim 3, wherein said deflector has the bottom portion flat and resting along one edge against the bottom of the box in the forwardly directed opening, the upper portion being positioned at its lower edge a substantial distance forwardly of the last mentioned opening and extending upwardly and rearwardly toward said flange and the said means connecting the upper portion with the flange comprising a pair of fingers projecting upwardly behind the flange.

HAROLD MITTON.
